(57) **CLAIM**

The ornamental design for a round flame heater, as shown and described.

DESCRIPTION

FIG. 1 is a front side view of a round flame heater showing my new design;

FIG. 2 is a left side view thereof;

FIG. 3 is a right side view thereof;

FIG. 4 is a rear side view thereof; and,

FIG. 5 is a top plan view thereof.

A bottom view is omitted because it is plain and unornamental and forms no part of the subject matter of the claimed design.

The broken line showings of FIGS. 1-4 are environmental only and not part of the claimed design.

In the drawings, the broken lines depict unclaimed subject matter only and form no part of the claimed design.
